ATTORNEY.

UNITED STATES PATENT OFFICE.

WILFRED LEWIS, OF HAVERFORD, PENNSYLVANIA, ASSIGNOR TO THE Tabor MANUFACTURING COMPANY, OF PHILADELPHIA, PENNSYLVANIA, A CORPORATION OF PENNSYLVANIA.

MOLDING-MACHINE.

1,259,883.

Specification of Letters Patent. Patented Mar. 19, 1918.

Application filed November 15, 1917. Serial No. 202,185.

To all whom it may concern:

Be it known that I, WILFRED LEWIS, a citizen of the United States, residing at Haverford, in the county of Montgomery and 5 State of Pennsylvania, have invented certain new and useful Improvements in Molding-Machines, of which the following is a specification.

The present invention relates to improvements in molding machines of the type constituting the subject-matter of my application, Serial No. 183,055, filed July 27th, 1917, and its principal objects are to effect an economy and improvement in the application 10 and use of the fluid under pressure by which the machine is operated, and to provide simple features of construction by which this can be accomplished.

The invention will be claimed at the end 15 hereof, but will be first described in connection with the embodiment of it chosen for illustration in the accompanying drawings forming part hereof and in which there is illustrated, principally in central section, so 20 much of a molding machine as is necessary for a description of the invention.

In the drawings 1, is a cylindrical plunger chamber provided internally with spaced or 25 separate port-channels 25, shown as arranged diametrically. 3, is a plunger provided with an air supply passage 4, and with an annular seat 5, of reduced diameter and with a groove 6. 7, is a solid, uncut, deformable ring, hereinafter called a valve 30 ring, and it is loosely mounted on the plunger seat 5, and is provided with ports 8, in communication with the air passage 4, and arranged for coöperation with the port channels 25. By elliptical deformation the 35 valve ring is caused to hug the cylindrical wall of the chamber 1 at opposed points and in the neighborhood of the ports 8, as will be more fully described. 10, is a locking ring arranged in the groove 6, and operating 40 to support the valve ring 7. The locking ring 10, may be a split ring sprung over the end of the plunger after the valve ring has been slipped into its place thereon. 45 11, is a thimble introduced merely to cover 50 possible inaccuracies in alinement of the pistons 13 and the port holes 8 and it is shown as provided with generally spherical ends of which one rests in a taper or conical seat surrounding the port 8, and of which

the other rests in a similar seat 12, surrounding the opening through the hollow or tubular piston 13. One end of the piston 13, is exposed to the air supply 4. Two pistons and their complemental thimbles, diametrically arranged, are shown, and they operate 55 under air pressure to deform or spring the valve ring 7, somewhat elliptically and cause it to make a tight joint with the wall of the chamber 1, in the neighborhood or vicinity of the ports 8, and also to make 60 tight joints between the abutting ends of the thimbles 11, and the ring 7, and the piston 13. This operation occurs when the parts are in the positions shown, because the pressure on the ends of the pistons 13, near 65 the supply passage 4, is greater than the pressure in the space 1, and it also occurs when the plunger 3, is in elevated position, with the ports 8, above the top walls of the port-channels 25. 18, is a spring between 70 the piston 13, and when present it holds the pistons 13, thimbles 11 and ring 7 in firm initial contact. Since proper packing is provided by the ring 7, and by the thimbles 75 it follows that air under pressure may not 80 blow through into the space 1, and thus an economy is effected and an improved mode of operation attained. If the ring 7 wears, loose the original pressure can be readily restored by slightly peening the ring on a 85 diameter at right angles to the ports 8. The effect of this peening is to give the ring a slight departure from circular form, causing it to hug the cylinder walls where close contact is desired to prevent leakage and 90 waste of air. The space between the ring and its seat 5, limits the amount of eccentricity ultimately obtainable. As the ring 95 swells or is deformed in one direction if comes in or contracts in the other, but a small difference will insure a very long life.

Inasmuch as the end of the plunger 3, and the cushion 17 (preferably of cork), contact to limit and fix the relative positions of the ports 8, and openings 2, as well as of other 100 parts of the machine, a nice adjustment is required. This adjustment is provided by a cavity 14, between the cushion 17 and the head of the chamber 1, which cavity is provided with a sprue opening 15, through 105 which a liner 16, of fusible metal is run. The liner 16, can be poured in while the machine is inverted with its parts wedged or

otherwise held in proper relative positions by means of a pouring stand or plunger giving the proper depth of chamber and which is inserted in the inverted chamber.

5 The machine is capable of a variety of uses.

Its mode of operation in shockless jar molding is as follows: The port 100 is connected with the atmosphere and air is introduced at the inlet 101. The air traverses the passage 4, the openings 8, into the space a , raising the plunger 3 until air escapes by 2 into the hollow base of the machine and raises the anvil member 102, which meets the 15 descending plunger and thereafter air escapes at 100. All of this occurs in the ordinary and well understood manner.

The machine can be used as a squeezer. For this purpose air is admitted at 100, with 20 the result that the anvil and everything connected with it and carried by it is lifted toward a head, which is too common a provision of molding machines to require illustration.

25 By removing the spring 103 and admitting air at 101, the machine will operate as an ordinary jarring machine and the shock will be taken by the base of the machine.

What I claim is:

30 1. In a molding machine the combination of a plunger chamber and a plunger formed with ports of which the walls constitute valves, a cushion in the head of the chamber for coöperation with the plunger to limit its 35 stroke, a cavity arranged between the cushion and chamber head and having a sprue opening through the head, and a liner of fusible metal arranged in the cavity, substantially as described.

40 2. In a molding machine the combination of a plunger chamber provided internally with spaced port-channels, a plunger provided with an air supply passage, a deformable valve ring mounted on the plunger and having ports in communication with the air passage and arranged for coöperation with the 45 wall of the chamber near the channels, and pistons carried by the plunger and exposed to the air supply and operating to deform 50 the ring elliptically against the chamber wall, substantially as described.

3. In a molding machine the combination of a plunger-chamber provided internally with spaced port-channels, a plunger provided with an air supply passage and having an external seat of reduced diameter and a 55 groove, a deformable valve ring loosely mounted on the plunger seat and having ports in communication with said air pas-

sage and arranged for coöperation with said channels and with the wall of the chamber, a locking ring in said groove for supporting the valve ring, thimbles having packing joint contact with the inner face of the valve ring, and tubular pistons carried by the 60 plunger and having packing joint contact with the thimbles and exposed to said air supply and operating on the thimbles to deform the packing ring elliptically against the chamber wall, substantially as described. 70

4. In a molding machine the combination of a plunger chamber provided internally with spaced port channels, a plunger provided with an air supply passage and having an external seat of reduced diameter and a 75 groove, a deformable valve ring loosely mounted on the seat and having taper seats and ports in communication with the air passage and arranged for coöperation with the wall of the chamber and with said channels, a locking ring in said groove for supporting the valve ring, tubular pistons carried by the plunger and exposed to the air supply and provided with taper seats, and thimbles having spherical ends adapted to 80 said taper seats, substantially as described.

5. In a molding machine the combination of a plunger chamber provided internally with spaced port-channels, a plunger provided with an air supply passage, a continuous deformable valve ring mounted on the plunger and having ports in communication with the air passage, tubular pistons carried by the plunger and exposed to the air supply, and thimbles interposed between the 90 pistons and ring, substantially as described. 95

6. In a molding machine the combination of a plunger chamber provided internally with spaced port-channels, a plunger provided with an air supply passage and with 100 a reduced seat and a groove, a valve ring loosely mounted on the seat and provided with ports in communication with the air supply, a locking ring in the groove for supporting the valve ring, and pistons carried 105 by the plunger and exposed to the air supply and operating to deform the valve ring elliptically, substantially as described.

7. In a molding machine the combination of a plunger chamber having ports in opposed portions of its wall, a plunger, a solid deformable ring mounted loosely on the plunger, and means for deforming the ring elliptically against opposed portions of the chamber wall to function the ring as a valve, 110 substantially as described. 115

WILFRED LEWIS.
